UNITED STATES PATENT OFFICE

DANIEL R. FRANCIS, OF WATERBURY, CONNECTICUT, ASSIGNOR TO THE WATERBURY TOOL COMPANY, OF WATERBURY, CONNECTICUT, A CORPORATION OF CONNECTICUT

DRIVING MEANS FOR ROTARY KNIVES OF PAPER MACHINES

Application filed December 27, 1928. Serial No. 328,735.

This invention relates to paper machinery and has for its principal object to provide a new and improved construction of a driving means for the rotary paper cutter, usually provided at the end of paper making machines, to cut off from the paper web as it comes from the machine, sheets of any desired length.

In the manufacture of paper it is a common practice to cut the paper into sheets of various lengths according to the specifications or demands of the purchaser. It has not been found practical in the past to cut the paper web as it leaves the paper machine into sheets of the desired length with sufficient accuracy and therefore it has been the practice to set the rotary paper knife, provided at the end of the paper machine, so that the sheets cut by such knife will be sufficiently longer than the proper length to afford the necessary material for trimming the paper in a paper cutting machine into sheets of the required length. Because of the fact that the speed of the paper machine is varied for different weights of paper, or different grades of stock, it becomes necessary to vary the adjustment of the rotary paper knife of the paper machine from time to time even when a constant length of cut sheet is desired. A variation of the speed of the rotary paper cutter is also necessary whenever sheets of different lengths are required by the specifications.

Various forms of change speed drives have been employed in the past for permitting the speed of the rotary paper cutter to be adjusted. Variable speed motors, cone pulleys and the like have heretofore been commonly employed for driving the paper knife. Such drives as have heretofore been used have given considerable difficulty because of the fact that it was impossible to adjust them to secure accurate and uniform cutting of the paper web into sheets of the proper length. It was therefore the practice, in order to avoid cutting the sheets too short, to adjust the rotary knife so that it would cut the web into sheets quite a considerable amount longer than necessary for providing the required margin for the final trimming of the paper. As will be readily understood the excess

trimming margin left on the sheets for the final trimming operation constitutes waste and this waste in the past has amounted to a considerable percentage of the whole production. It is the object of the present invention to provide a new and improved drive for the rotary paper knife of the paper machine by means of which the relative speed of such knife to the linear speed of the paper web can be proportioned with great accuracy and uniformity of operation.

The above and other objects will appear more fully from the following more detailed description and by reference to the accompanying drawings forming a part hereof and wherein Fig. 1 is a plan view of a delivery end of a paper machine showing the installation and application, constructed in accordance with the principles of this invention, of a drive for the rotary knife of the paper machine; Fig. 2 is a side elevation of the structure shown in Fig. 1 and Fig. 3 is an enlarged view partly in elevation and partly in section showing one of the units of the driving means for the paper knife.

As shown in the drawings, the numeral 10 indicates a battery of drier rolls such as ordinarily located at the delivery end of a paper machine. The web of paper passes from the drier rolls and under the rotary paper knife 11 in accordance with the usual practice. The shaft of the paper knife 11 has connected to it, by means of a flexible coupling 12, the driving shaft of a hydraulic motor 13. Fluid under pressure from a hydraulic pump 14 is supplied to the motor 13 through the pipes 15 and 16.

The hydraulic pump 14 is driven from any of the rotating members or shafts of the paper machine whose speed of rotation is proportional to the linear speed of the paper web delivered by the machine.

In the particular constructional example disclosed the pump 14 has its driving shaft connected, by means of a flexible coupling, to a shaft extension 17, the latter being supported in bearings 18, 19 supported upon any suitable foundation, such as the base plate 20. Located between the bearings 18 and 19 and keyed to the shaft extension 17 is a chain gear 100

21. A chain preferably of the silent chain type is trained about the gear 21 and a gear 22, the latter being keyed to a shaft extension 23 of the drying roll drive. 70
- 5 22. The hydraulic pump and motor, 14 and 13 respectively, are preferably of the type known as the Waterbury gear and each includes a rotary cylinder barrel 25, see Fig. 3, mounted upon a driving shaft 26. The barrel 25 has formed therein a plurality of cylinders 27 which extend in parallelism with the driving shaft. Each cylinder has mounted for reciprocation therein a piston 28. The pistons 28 are connected by piston rods 29 with a swash plate 30 mounted for rotation within a tilting box 31. In accordance with the usual construction of the Waterbury type gearing, the tilting box of the motor 13, or B-end, as it is usually called, is held at a 10 fixed inclination to the driving shaft 26, while the tilting box of the pump, or A-end, 14 may have its angle to the driving shaft 26 varied as desired. Means are provided for adjusting the tilting box and swash plate 15 of the motor and such means consist of a control shaft 32, which, in the particular constructional example disclosed, is provided with a screwthreaded portion which engages the screwthreads of a rotatable nut 33. When 20 the motor, swash plate and tilting box are set by the control shaft to extend at right angles to the driving shaft 26, the pistons 28 will have no stroke and no fluid will be delivered by the pump. This is called the 25 neutral position of the gear. When the tilting box and swash plate are inclined in either direction from the neutral position, fluid will be pumped in one or the other direction through the pipes 15 and 16, and the amount 30 of fluid so pumped, or the output, will increase proportionately to the extent of the inclination given to the swash plate and tilting box. 105
- 35 In the particular constructional example 45 herein disclosed, the adjustment of the control shaft 32 is effected by means of a manually operable hand wheel 35, preferably secured upon a hand wheel shaft 36, mounted for rotation in bearings 37 upon the side of 50 the supporting bracket or standard 38 in which the ends of the shaft of the paper cutting knife are journaled. Secured to the hand wheel shaft 36 is a sprocket gear 39 about which and a similar sprocket 40 is 55 trained a sprocket chain 40*. The sprocket 40 is mounted upon one end of a shaft 41 extending longitudinally of, and suitably supported upon, the side frame of the paper machine. The shaft 41 is connected by 60 means of a second chain and sprocket connection 42 with one end of a second longitudinal shaft 43. The other end of the shaft 43 extends into a gear reduction box 44 which 65 box is provided with suitable reduction gear- 110 ing by means of which the rotation of the shaft 43 is communicated to a vertically extending shaft 45 the upper end of which extends into the gear box 44 and the lower end of which is suitably connected to the control shaft nut 33. 115
- 70 The manner in which the installation operates is as follows: When the paper machine is in operation the rotation of the shaft 23 of the drier drive will be communicated through the chain drives 21, 22 to the driving shaft of the pump 14. The control shaft 32 of the pump is adjusted by means of the hand wheel 35 and the connecting gears and shafts 39 to 45 inclusive to bring about a 75 delivery of fluid by the pump for producing a rotation of the hydraulic motor 13 and the rotary paper knife 11 at the desired speed 80 relatively to the linear speed of delivery of the paper for cutting the web into sheets of desired length. As the hydraulic speed gear 85 is capable of infinite speed variation the exact setting of the control shaft is easily obtained for any desired length of sheet. When the control shaft has once been set, the drive of the paper knife will be so accurate 90 and positive that the margin left for trim is practically negligible. As the hydraulic drive operates with a practically incompressible fluid, such as oil, no fluctuations or 95 variations in speed of the gear can occur and consequently the paper knife will continue to operate uniformly at the proper speed. If the speed of the paper machine is varied for any reason whatsoever the ratio of the 100 speed of rotation of the paper knife to the linear speed of delivery of the paper will not be varied because of the fact that the pump of the hydraulic speed gear is driven directly by one of the rotating parts of the paper machine. 105
- 110 In the particular constructional example disclosed, the pump of the hydraulic gear has been located at a point quite distant from the motor 13. This arrangement however is merely illustrative. Obviously the pump 115 may be located at any desirable point, for example, the pump or A-end might be driven from the variable speed line of the paper machine, or if for any cause it should be found desirable to locate the pump at even a greater distance from the motor than shown in the drawings, the latter could readily be done because of the fact that the fluid circulated from the pump to the motor through the pipe lines 15, 16 and as such pipe lines 120 may be bent in any desired direction and the length thereof is immaterial. It will be understood that the constructional details of the gearing and shaft connections between the hand wheel 35 and control shaft 32 of the 125 motor are merely illustrative of a satisfactory constructional example and that the invention is not limited to such details but that many changes, variations and modifications 130 of these details as well as other minor details 130

of the installation disclosed may be resorted to without departing from the principles of the invention.

I claim:

- 5 1. In a machine for cutting a travelling web of material, driving means for said web of material, a rotary web cutting knife, and variable speed means for driving said knife, said variable speed means comprising a fluid 10 pressure pump, driving connections between said pump and said first named driving means whereby the speed of said pump is determined by the speed of travel of said web, a fluid pressure motor, driving connections between said motor and knife, said pump having an adjustable control shaft by means of which its rate of output may be varied infinitely between predetermined limits, a manually operable adjusting device located immediately adjacent to said paper knife, gearing connections between said adjusting device and said control shaft, and connections between said pump and motor whereby the operative speed of said knife bears a predetermined relation to the speed of travel of said web and is automatically maintained in said relation regardless of variations in said speed of travel of the web.
- 20 2. The combination with the rotary paper cutting knife of a paper cutting machine, of means for automatically maintaining a precise, accurate adjustment of the speed of rotation of said knife relatively to the linear speed of the paper delivered by said machine whereby said knife will cut said paper into sheets of uniform length irrespective of variations in the absolute linear speed of said paper, said means comprising a rotary fluid pressure pump, positive driving connections 25 of invariable effect between a rotating part of said paper machine and said pump, a rotary fluid pressure motor, positive driving connections between said motor and said paper knife, and conduits connecting said pump and motor, said pump being provided with an adjustable control shaft for varying its output and thereby the speed of said motor, a manually operable hand wheel located adjacent to said rotary knife and gearing connecting said hand wheel and the control shaft of said pump, said gearing including a reduction gear whereby a relatively large movement of said hand wheel will produce a small extent of movement of said control shaft thereby enabling a fine adjustment of the output of said pump and a similar adjustment of the speed of rotation of said motor and knife to be secured.

In testimony whereof I have hereunto set
60 my hand.

DANIEL R. FRANCIS.
